UNITED STATES PATENT OFFICE.

HAAKON A. MARTIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

LOCKING MECHANISM FOR CASH-REGISTERS.

1,215,567.

Specification of Letters Patent. Patented Feb. 13, 1917.

Application filed July 13, 1914. Serial No. 850,653.

To all whom it may concern:

Be it known that I, HAAKON A. MARTIN, a citizen of the United States, residing at Dayton, in the county of Montgomery and 5 State of Ohio, have invented certain new and useful Improvements in Locking Mechanism for Cash-Registers, of which I declare the following to be a full, clear, and exact description.

10 This invention relates to cash registers, accounting machines and the like and has more particular reference to detent mechanism which is operated and rendered effective in connection with the manipulative 15 devices of cash registers, adding machines and other machines employing manipulative devices of like nature.

The principal object of this invention is to so construct a detent mechanism for depressible keys, that the keys cannot be operated to perform one of their functions and wrongfully and immediately be returned to undepressed position before their other functions are performed or before the 25 proper time for their release during the operation of the machine. Another object of the machine is to provide a detent mechanism adapted to perform certain functions entirely independent and beyond the control 30 of the operator, which functions have heretofore been under control of the operator through the possibility of improper manipulation of the keys or other devices.

In the preferred form of embodiment disclosed herein, an improved detent mechanism is provided for locking the keys in depressed position and unlocking the operating mechanism and this means is so constructed that the keys cannot be operated 40 adroitly to release the operating mechanism and immediately returned to undepressed position. This improved detent mechanism in the illustrative form disclosed herein, comprises a single key locking detent 45 and a device operated by automatic means, such as a spring, the automatic means being designed to operate the detent for the purpose of releasing the machine after the detent has been operated partially by a key. 50 These keys, employed to release the machine, may be clerks' keys or transaction keys for performing any one or more of the well known functions usually performed by such keys or they may be amount keys for controlling the differential mechanism for ac- 55 counting devices. For the sake of convenience these releasing keys will be called initial keys herein.

Heretofore, in machines employing a single detent for locking keys in depressed position and releasing the machine it was found difficult to construct the parts so accurately that the keys would be locked by the detent at the very instant that the machine was released. If the parts were not accurately constructed the keys might be depressed gently and gradually to operate the detent sufficiently to release the machine but not sufficiently to lock the depressed key in depressed position. Under such conditions, as soon as the operating mechanism was released and its operation begun the key could be returned to normal position without performing its other functions during the operation of the machine. Furthermore with the single detent constructions, heretofore known, it was possible sometimes to give a key a sharp blow to release the operating mechanism, the key being quickly pulled out before the detent moved into position to lock it in depressed position. Such operations of a key would be effective to release the machine but as the key would not be retained in position to perform its other functions as for example controlling an indicator or type carrier, during the operation of the machine an incomplete or incorrect indication or record would be entered in the machine thereby enabling the person operating the machine to perpetrate a fraud. To avoid these objections some well known machines, employ two detents, one detent being used to retain the keys in depressed position while the other detent releases the machine so that the operating mechanism can not be released until the depressed key is locked in by the key locking detent. Even with the use of two detents, however, it has been found that a very close timing of the parts is necessary and, therefore, in some machines devices are used in conjunction with the two detents to insure their proper operation. While the use of two detents, especially in connection with other devices insuring their proper operation, is very effective in performing their desired function, the detent mechanism of the present invention which employs but one detent has advantages over the two detent construction as the present detent 100 105 110

mechanism is just as effective, the cost of construction less, and as there is one instead of two detents, the keys are easier to operate. A further object of this invention is to provide means, in connection with the present improved detent mechanism, to prevent a second operation of the machine when one of the releasing keys is held manually in depressed position until after the end of an operation of the machine.

The particular form of machine to which the present invention is shown applied is that disclosed in Letters Patent of the United States, issued April 13, 1897, to J. P. Cleal and F. A. Reinhard and numbered 580,378 and June 29, 1915, to Charles F. Kettering and William A. Chryst, numbered 1,144,418. It is not intended, however, to limit the invention to use with this particular type of machine as the invention is susceptible of use in other types of machines without departing from the scope of the present invention.

With these and incidental objects in view the invention consists of certain novel features of construction and combination of parts the essential elements of which are set forth in appended claims and a preferred form of embodiment of which is hereinafter described with reference to the drawings which accompany and form part of this specification.

Of said drawings:

Figure 1 is a left hand side elevation of the type of machine, shown in the above mentioned patent, with certain parts omitted and the upper part of the machine broken away and showing the present invention applied thereto.

Fig. 2 is a detail view of the locking pawl and disk for normally locking the operating mechanism against operation.

Fig. 3 is a partial detail view showing the detent mechanism of the present invention in operated position.

Fig. 4 is a right hand side elevation of the machine with the upper part of the machine broken away and showing locking means for the motor driven operating mechanism.

Fig. 5 is a right hand side elevation of the machine showing the motor driving means.

The type of machine to which the present improvements are shown applied is old and well known and need not be described in detail here. This type of machine in general comprises a plurality of amount keys 10 (Fig. 4) which act to control the differential adjustment of the differential mechanism for accounting devices. This differential mechanism and the accounting devices are not shown in the present application as they form no part, and are not necessary to the understanding, of the present invention. The differential mechanism is driven by op-

erating segments 11, see Fig. 1, fast on a shaft 12, there being one of these segments for each bank of amount keys. The shaft 12 and segments 11 are rocked first clockwise as viewed in Fig. 1, then counter clockwise past normal position and finally clockwise to normal position (as shown in Fig. 1) by the main operating shaft 13 through the medium of mechanism not shown in the present drawings.

As shown in Fig. 1, the left hand bank of keys comprises two classes of keys, *i. e.* amount keys 10 and initial keys 14 the two upper keys being amount keys and the seven lower keys being initial keys. It is of course to be understood that the number of keys of each class in the bank may be varied or the amount keys 10 be entirely omitted from this bank if desired. There is a locking detent 15 for each bank of amount keys and one for the two amount keys shown in Fig. 1 and the keys when depressed, slightly rock the detents upwardly about the shaft 12 by the coöperation of the inner ends of the keys with slots (not shown) formed in the detent as is well known in the art and illustrated in the hereinbefore mentioned patent. The locking detent 15 for the two amount keys shown in Fig. 1 coöperates only with the amount keys and not with the initial keys. When an amount key in any bank is depressed the detent 15 for the particular bank is raised and locks the other amount keys in the bank against operation during the operation of the machine. Upon the raising of a detent 15 a slidably mounted latch plate 16 is drawn rearwardly by its spring 17 to move a shoulder 18 on the plate under the lower forward end of the detent to lock the latter in its raised position and thereby lock the unoperated amount keys against operation. It is understood of course that there is one of these latch plates 16 for each detent 15.

To release the depressed amount keys during an operation of the machine to permit the keys to be restored to normal position by their springs 19 the driving segments 11 have downwardly extending projections 20 which near the end of the counter clockwise movement (Fig. 1) of the segments engage rollers 21 on the operated latch plates 16 to force the latter forwardly slightly past normal position shown in Fig. 1. The detents then are rocked downwardly by springs (not shown) and the lower forward edges of the detents are thereby moved into the path of movement of shoulders 22 on the latch plates 16 so that, when the segments 11 are rocked clockwise to normal position, the latch plates 16 will be drawn slightly rearwardly by their springs 17 and be stopped in normal positions by the shoulders 22.

The improved detent mechanism of the present invention for the initial keys 14 comprises a detent 24 (Figs. 1 and 3) hav-

ing notches 25 at its upper and lower ends straddling pins 26 to guide the detent in its movements. Pins 27 on the initial keys 14 project over the detent and when a key is depressed its pin engages an inclined edge 28 of the appropriate one of a series of slots 29 formed in the detent 24 and adjacent the pins 27 to elevate partially the detent 24, against the action of a spring 30 which is connected at its upper end to an arm 31 on the detent and at its lower end to the machine frame. The pins 32 on the amount keys do not project over the detent 24 and no slots 29 are provided therefor and therefore operation of one of these amount keys does not effect movement of the detent. The arm 31 carries a roller 33 normally engaging the rear edge of an arm 34 just below the lower side of a camming notch 35 formed in the upper rear edge of the arm 34. This arm 34 is fast on a shaft 37 which extends across the bottom of the machine and a spring 38, which is much superior in strength to the spring 30 tends to rock the arm 34 and shaft 37 counter clockwise as viewed in Figs. 1 and 3. When a key is depressed the detent 24 is raised sufficiently to carry the roller 33 into position to co-operate with the lower side of the notch 35, whereupon the arm 34 is rocked rearwardly by its spring 38. The lower side of the slot 35 is inclined to form a cam surface which co-operates with the roller 33 to elevate the detent 24 beyond the point to which it had been elevated by the depressed key 14 when the arm 34 is rocked rearwardly. The detent 24 is shown in its completely operated condition in Fig. 3 and it can be seen from this figure that hook projections 40 formed by the slots 29 in the detent 24 pass over the pin 27 on the operated initial key to lock it in depressed position and passes under the pins 27 on the unoperated keys to lock them against depression, it being understood of course that only one initial key is depressed at each operation of the machine. In the normal position of the plate 16 a roller 41 carried thereby stands a little to the left of the rear edge of the arm 34 as shown in Fig. 1. When the arm 34 is then rocked rearward or in a counter clockwise direction as shown in said Fig. 1, the rear edge of said arm will engage or be directly adjacent said roller 41. When the latch plate 16 is moved slightly past normal position near the end of the operation of the machine as already stated, the roller 41 rocks the arm 34 clockwise slightly past normal position to carry the notch 35 away from the roller 33 on the detent 24 whereupon the spring 30 draws the detent 24 downwardly to normal position to permit the depressed key to be restored to its undepressed position by its spring. Then as the segment and latch plate 16 are moved to normal position the

spring 38 rocks the arm 34 slightly counter clockwise to normal position wherein the rear edge of said arm will again rest against roller 33.

The machine in the present form of embodiment disclosed herein is shown as operated by an electric motor but it is to be understood that the machine may be operated by any other suitable means such as an operating handle, many of the machines of this type on the market being capable of being operated by either a motor or an operating handle, as desired. The locking device shown in Fig. 2 for locking the machine against operation when either an operating handle or a motor is used, will be described first in connection with the present invention and then the motor locking mechanism and connections shown in Fig. 4 will be described. Rigidly connected to an operating crank handle 39, the lower end of which is shown broken away in Fig. 4, is a gear 42 meshing with a large intermediate gear 56. The latter gear meshes with a gear 44 fast on a shaft 45. The main drive shaft 13 carries a gear 43 which meshes with the gear 44. The gears 43 and 44 have twice as many teeth as the gear 42 so that two rotations of the crank handle 39 is necessary to give the gears 43 and 44 and their shafts 95 one complete rotation at each operation of the machine. A locking disk 46 is fast on the shaft 45 and is provided with a notch 47 into which a nose 48 on a locking arm 49 normally projects normally to lock the shaft 45 against rotation. The arm 49 is fast on a shaft 50 which also carries fast thereon an arm 51 (Fig. 1). A spring (not shown) normally retains the arms 49 and 51 and shaft 50 in the position shown in Figs. 1 and 2. When the detent 24 is elevated partially by the complete depression of a key, an arm 52 on the detent is elevated so that it just engages with the under side of a projection 53 on the arm 51. Then continued movement of the detent 24 effected by arm 34 rocks the arm 51, shaft 50 and arm 49 through the engagement of arm 52 with the projection 53 so that the nose 48 on the arm 49 is carried partially out of the notch 47 in disk 46. Upon rotation of the shaft 45 the flat surface 54 of the disk 46 engages the nose 48 and rocks the latter still further clockwise as viewed in Fig. 2.

It can be seen from the above description that the present invention admirably fulfills its principal object of preventing a key from returning to normal position immediately after the operating mechanism is released. The machine cannot be released by a partial operation of the detent 24 as the key must be in its fully depressed position before the roller 33 is in position to be engaged by the lower edge of the notch 35, and even then the releasing of the machine

is beyond the control of the operator as the movement of the detent under control of the key has no effect on the arm 51 which is only engaged and moved by the detent 24 when the arm 34 is operated automatically by its spring 38. After a key is depressed fully, it cannot be moved to undepressed position, as the plate has been sufficiently elevated by the depressed key to carry the hook 40 over the pin 27 on the key and the arm 34 at this instant not only prevents the detent from returning to normal position but still further elevates the detent. It can be seen that if the lower cam edge of the slot 35 becomes worn down slightly so that the partial operation of a key will raise the roller 33 sufficiently to permit the arm 34 to be rocked rearwardly, the cam edge of the slot will elevate the detent 24 and the upper edge 93 of the hook projection 43 for the particular key will engage the pin 27 on the key and force the latter into its fully depressed position.

In the drawings only a portion of the motor clutch is shown (Fig. 4). This form of clutch and motor connections has become well known in the art and it is not thought necessary to describe it in detail in the present application as they are fully shown and described in the Kettering and Chryst patent hereinbefore mentioned. In general, the clutch comprises a clutch member 57 which is adapted to be given a slight preliminary movement about the shaft 58 under the action of a spring (not shown) to render the clutch effective. The clutch member 57, however, is normally restrained from such preliminary movement by the engagement of a flange 59 carried by the member 57 with a flange 60 formed on the rearwardly extending arm of a lever 61 which is pivoted at 62 to the right hand frame of the machine. The lever 61 on its rearwardly extending arm also carries a lug 63 normally engaging a shoulder 64 formed on a disk 65 fast on the shaft 45. As will be noted from the train of gearing comprising the gears 44 and 43 and the gear 66, which is fast on the shaft 58 rotated by the motor 50 and meshes with the gear 43 the shafts 13 and 45 are given a single rotation at each operation of the machine. A spring 67 tends to rock the lever 61 about its pivot to withdraw the lug 63 from engagement with the shoulder 64 on the disk 65 and also withdraw the flange 60 from the path of the flange 59 on the disk 57 to render the clutch effective. The movement of the lever 61 in this manner is prevented however by the engagement of a stud 68 on the lever 61 with the lower face of a projection 70 on an arm 71 fast on the shaft 37. It can be seen from the above description that when the shaft 37 is rocked by the movement of the arm 34 the projection 70 on the arm 71 is carried

away from the stud 68 on the lever 61 and the spring 67 immediately acts to rock the lever 61 about its pivot thereby releasing the motor operating mechanism as described. When the shafts 13 and 45 have been given nearly one rotation, during the operation of the machine a pin 72 on the gear 43 engages the under side of a block 73 on the rear end of the lever 61 thereby rocking the lever 61 back to normal locking position. Then when the arm 34, shaft 37 and arm 71 are rocked forwardly by the forward movement of the latch plate 16 (Fig. 1) as before described, the projection 70 on the arm 71 is carried into locking engagement with the pin 68 thereby locking the lever 61 against movement until the next operation of the machine.

The device to be now described is provided to prevent a second operation of the machine when one of the initial keys 14 is held in manually at the end of an operation. It has been found in practice that this is often attempted by persons who wish to operate the machine to cover such operations in which the proper amounts are not entered in the machine. In these attempts it is customary to push in one of the initial keys and hold it in depressed position at the end of the first operation thereby keeping the circuit for the motor closed and permitting an immediate second operation of the machine to destroy the indication of the first operation. The means in the present invention for preventing such misoperations comprises a pawl 75 (Figs. 1 and 3) mounted pivotally on the upper end of the arm 34 and the forward lower end of the pawl normally engages with the upper side of a forwardly extending projection 76 on the arm 31 of the detent 24. A spring 77, connected at its opposite ends to the pawl 75 and a pin on arm 34, tends to pull the pawl 75 downward and a pin 74 on the arm 34 is used to prevent the pawl from being drawn down past normal position. It is apparent that when an initial key is depressed and the detent 24 raised thereby, the pawl 75 will be rocked upwardly and then when the arm 34 is rocked the lower side of the pawl merely slides on the upper side of the projection 76, as shown in Fig. 3. When the arm 34, however, is rocked forwardly past normal position near the end of the operation of the machine as above described, the pawl 75 is carried forwardly an extent sufficient to slide out of engagement with the projection 76 and then its spring 77 draws the pawl downwardly into normal engagement with the pin 74. If the depressed initial key is held in depressed position at the end of the operation of the machine the arm 34 cannot be rocked back slightly to normal position as the rear edge of the pawl 75 abuts against the forward end of the projection 76 which is then held elevated by the key held depressed, and in

this position of the parts a projection 78 on the rear end of the pawl 75 engages under the projection 76 to retain the detent 24 in its partially operated position the detent having 5 been lowered to this position by its spring 30. From the above description it is obvious that when a depressed initial key is retained in depressed condition at the end of the operation of the machine the arms 34 and 71 10 are prevented from rocking rearwardly by the engagement of the forward end of the pawl 75 with the projection 76 to prevent the arm 34 from again raising the detent 24 whereby a second operation of the machine 15 is prevented.

It is customary in machines of the present type to provide means so that when an amount key is depressed in error it can be released before an operation of the machine 20 is begun and this same means in the present invention is employed to rock the arm 34 to carry the pawl 75 out of engagement with the projection 76 when an initial key has been held in depressed position at the end 25 of the operation of the machine. This means comprises the shaft 80 extending longitudinally across the front of the machine and bearing pins 81 (Fig. 1) each of which is normally out of engagement with a corresponding pin 82 on the forward end of the latch plate 16. The shaft 80, as shown in Fig. 4, has fast on its right hand end a small operating lever 83 and a spring 84 normally retains the lever 83 and shaft 80 in the position shown in this figure. When it is desired to release an amount key before the operation of the machine is begun it is necessary merely to press down on the forward end of the lever 83 thereby rocking the shaft 30 80 to cause the pins 81 to engage the pins 82 so as to draw the operated latch plates 16 forwardly a sufficient extent to withdraw the locking shoulder 18 from beneath the elevated detents 15 thereby permitting the release of the amount keys. It can be seen that when the latch plate 16, shown in Fig. 1, is drawn forwardly its roller 41 engages the arm 34 and rocks the latter slightly to carry the pawl 75 out of engagement with the projection 76. The spring 30 then acts immediately to draw the detent 24 to normal position. Finally when the lever 83 is released the arm 34 and latch plate 16 are returned to the normal positions shown in Fig. 1.

55 A lever 88 (Fig. 4) is pivoted at 85 to the frame of the machine and at its forward end is provided with a slot 86 that straddles a pin 87 on the handle 83. When the handle 83 is depressed the lever 88 is rocked and a 60 projection 89 on the lever passes into a notch 90 formed by a projection 91 on the arm 71. While the machine is in operation, the projection 91 on the arm 71 is under the projection 89 on the lever so that movement of the lever 88 at such time is prevented and hence

the handle 83 cannot be moved to release the amount keys during an operation of the machine.

The pawl 75 is provided with the projection 78 for retaining the detent 24 in partially operated position so that an initial key which has been held in at the end of the operation will be retained in depressed position by the detent plate 24 after the operator removes his finger from the key. As 70 the key is in depressed position the person attempting to again operate the machine can see at a glance at the keyboard that it is first necessary to operate the lever 83 to release the key. If this projection 78 was not provided, the friction existing between the projection 76 and the rear end of the pawl 75 might be sufficient to retain the detent 24 in a slightly elevated position when the operator removes his finger from the depressed key 75 after the end of the operation of the machine. The pin 27 on the key at this time, if the projection 78 was not provided would engage the inclined edge 93 of the hook projection 40 as the key moves to its normal position, this movement of the key being sufficient to slightly lower the detent 24 to permit the return of the key to normal position but not sufficient to move the detent 24 to normal position and therefore the rear end of the pawl 75 would still engage the projection 76 and prevent arm 34 from being rocked rearwardly to release the machine when the same or another initial key was depressed. With 80 the machine in this condition it can be seen that a clerk might attempt to operate the machine and consider the machine out of order because it could not be operated upon depression of his key, the clerk being liable to forget to operate the lever 83. However 85 with the present construction, employing the projection 78 as soon as the clerk perceives that one of the initial keys is locked in it would occur instantly to him to operate the lever 83 and place the machine in condition 90 for operation.

It is thought that the above description is sufficient for a complete understanding of the invention and therefore a detailed description of its operation will not be given here. Briefly however, it may be stated that the present invention is well adapted to perform its proper objects, as the machine is provided with one detent which is operated first partially by the operator and then 100 automatically by means beyond the control of the operator. By such a construction it is impossible for the machine to be released and for the initial key to be returned to normal position before the proper time during the operation of the machine.

While the form of mechanism here shown and described, is admirably adapted to fulfil the objects primarily stated, it is to be understood that it is not intended to con- 105 110 115 120 125 130

fine the invention to the one form of embodiment herein disclosed, for it is susceptible of embodiment in various forms all coming within the scope of the claims which 5 follow.

What is claimed is:—

1. In a machine of the class described the combination with operating means, of a normally effective locking device therefor, a 10 plate having two movements for rendering said locking device ineffective, depressible keys for giving said plate one movement, and means for automatically giving said plate its second movement when the plate 15 has received its first movement.
2. In a machine of the class described the combination with operating means, of a normally effective locking device therefor, a plate having two movements for rendering 20 said locking device ineffective, depressible keys for giving said plate one movement, and spring means for giving said plate its second movement when the plate has received its first movement.
3. In a machine of the class described the combination with operating means, of a normally effective locking device therefor, depressible keys, means for rendering said locking device ineffective and for locking 25 the depressed keys in depressed position and partially operated by said keys, and means for automatically completing the operation of said rendering means, when a key is depressed completely, to render said locking 30 device ineffective and lock the depressed key in depressed position.
4. In a machine of the class described the combination with operating means, of a normally effective locking device therefor, depressible keys, a detent plate having hook 35 projections, for locking the keys in depressed position, and inclined edges, and capable of having two movements to render said locking device ineffective, one of the 40 movements being given thereto by the co-operation of the depressed keys with said inclined edges, and a spring operated member having a camming surface for engaging said detent to give the latter its second 45 movement when one of said keys is fully depressed.
5. In a machine of the class described the combination with operating means, of a normally effective locking device therefor, depressible keys, a detent plate having inclined edges and hook projections, for locking 50 the keys in depressed position, and capable of having two movements to render said locking device ineffective, one of the movements being given thereto by the co-operation of the depressed keys with said inclined edges, and means, automatically operated, for giving said detent its second movement when one of said keys is fully depressed.
6. In a machine of the class described the

combination with operating means, of a normally effective locking device therefor, depressible keys, a detent, normally out of operative relation with said locking device, capable of receiving two movements to render 70 said locking device ineffective, and provided with means for locking the depressed keys in operated position, one movement of the detent being imparted thereto by the keys to move the detent into operative relation with said locking device, and means for automatically giving said detent its second movement to move said locking device out of locking position and lock the depressed keys in depressed position.

7. In a machine of the class described the combination with operating means, of a normally effective locking device therefor, depressible keys, a detent plate having inclined edges and hook projections, for locking 75 the depressed keys in depressed position, and the undepressed keys in normal position, and capable of having two movements to render said locking device ineffective, one of the movements being given thereto by the co-operation of the depressed keys with said inclined edges, and means, automatically operated, for giving said detent its second movement when one of said keys is fully depressed.

8. In a machine of the class described the combination with operating means, of a normally effective locking device therefor, depressible keys, a detent, normally out of operative relation with said locking device, capable of receiving two movements to render 90 said locking device ineffective, and provided with means for locking the depressed keys in operated position, and adapted to lock the undepressed keys against operation, one movement of the detent being imparted thereto by the keys to move the detent into operative relation with said locking device, and means for automatically giving said detent its second movement to move said locking device out of locking position and lock the depressed keys in depressed position and the undepressed keys in normal position.

9. In a machine of the class described the combination with operating means, of a locking device therefor normally in locking position, depressible keys, a detent normally out of operative relation with said locking device, capable of receiving two movements to move said locking device out of locking position, and provided with means for locking the keys in depressed position one movement of the detent being imparted thereto by the keys to move the detent in operative 115 relation with said locking device, and a spring operated camming device for giving said detent its second movement to move the locking device out of locking position.

10. In a machine of the class described 120

- the combination with operating means, of a normally effective locking device therefor, means for rendering said locking device ineffective and having two movements 5 to accomplish this purpose, manipulative means for imparting one movement to said rendering means, automatic means for giving said rendering means the other movement, and means for preventing a second 10 operation of said automatic means when a key is retained in depressed position at the end of an operation of the machine.
11. In a machine of the class described the combination with operating means, of a normally effective locking device therefor, means for rendering said locking device ineffective and having two movements 15 to accomplish this purpose, manipulative means for imparting one movement to said rendering means, automatic means for giving said rendering means the other movement, and a pawl carried by said automatic means for preventing a second operation of said automatic means when a key is retained 20 in depressed position at the end of an operation of the machine.
12. In a machine of the class described the combination with operating means, of a normally effective locking device therefor, for a plate having two movements for rendering said locking device ineffective, depressible keys for giving said plate one movement, means for automatically giving said plate its second movement when the 25 plate has received its first movement, and means for retaining said plate in the position to which it is moved by said keys and for preventing a second operation of said automatic means when a key is held in depressed position at the end of an operation of the machine.
13. In a machine of the class described the combination with operating means, of a normally effective locking device therefor, 30 depressible keys, means for rendering said locking device ineffective and for locking the depressed keys in depressed position and partially operated by said keys, means for automatically completing the operation 35 of said rendering means, when a key is depressed completely, to render said locking device ineffective, and means for retaining said rendering and locking means in partially operated position and for preventing 40 a second operation of said automatic means when a key is held in at the operation of the machine.
14. In a machine of the class described the combination with operating means, of a normally effective locking device therefor, 45 depressible keys, a detent plate having inclined edges and hook projections for locking the keys in depressed position and capable of having two movements to render said locking device ineffective one of the movements 50 being given thereto by coöperation of the depressed keys with said inclined edges, means, automatically operated, for giving said detent its second movement when one of said keys is fully depressed, and means for retaining said detent in partially operated position to lock a key in depressed position after an operation of the machine if the key is held in manually until at the end of the operation of the machine. 70
15. In a machine of the class described the combination with operating means, of a normally effective locking device therefor, depressible keys a detent, normally out of operative relation with said locking device, capable of receiving two movements to render said locking device ineffective, and provided with means for locking the depressed keys in operated position, one movement of the detent being imparted thereto by the 75 keys to move the detent into operative relation with said locking device, means for automatically giving said detent its second movement to move said locking device out of locking position, and means for preventing a second operation of said automatic means if a key is held manually in depressed position until after the machine has been operated. 80
16. In a machine of the class described the combination with operating means, of a normally effective locking device therefor, depressible keys, a detent, normally out of operative relation with said locking device, capable of receiving two movements to render 85 said locking device ineffective, and provided with means for locking the depressed keys in operated position one movement of the detent being imparted thereto by the keys to move the detent into operative relation 90 with said locking device, means for automatically giving said detent its second movement to move said locking device out of locking position, and means for preventing a second operation of said automatic means if a key is held manually in depressed position until after the machine has been operated. 95
17. In a machine of the class described the combination with an operating mechanism, of a normally effective locking device therefor, a cam member for rendering said locking device ineffective, means for automatically operating said cam member 100 to render the locking device ineffective, depressible keys controlling the operation of said automatic means, and means for preventing a second operation of said automatic means when a key is held manually 105 in depressed position until after the operation of the machine. 115
18. In a machine of the class described the combination with an operating mechanism, of a normally effective locking de- 120

vice therefor, a plate having two movements the second of which renders said locking device ineffective, depressible keys for giving said plate one movement, automatic means controlled by said plate for giving said plate its second movement, a motor for driving said operating mechanism, and a locking device for rendering said motor ineffective and controlled by said automatic 10 means.

19. In a machine of the class described the combination with an operating mechanism, of a normally effective locking device therefor, a plate having two movements the second of which renders said locking device ineffective, depressible keys for giving said plate one movement, the keys being locked in depressed position by said plate, automatic means, controlled by 15 said plate, for giving said plate its second movement, a motor for driving said operating mechanism, and a locking device for rendering said motor ineffective and controlled by said automatic means.

20. In a machine of the class described the combination with an operating mechanism of a normally effective locking device therefor, a plate having two movements the second of which renders said locking device 25 ineffective, depressible keys for giving said plate one movement, automatic means, controlled by said plate, for giving said plate its second movement, a motor for driving said operating mechanism, a normally effective spring operated locking device for rendering the motor ineffective, and connections from said automatic means for normally holding the motor locking device in effective position and operated by said 30 automatic means when the automatic means gives said plate its second movement, to release said motor locking device.

21. In a machine of the class described the combination with operating means, of a normally effective device therefor, means for rendering said locking device ineffective and having two movements to accomplish this purpose, manipulative means for imparting one movement to said rendering means, automatic means for giving said rendering means the other movement, means for preventing a second operation of said automatic means when a key is retained in depressed position at the end of an operation of the 45 machine, and means for disabling said preventing means.

22. In a machine of the class described the combination with operating means, of a normally effective locking device therefor, means for rendering said locking device ineffective and having two movements to accomplish this purpose, manipulative means for imparting one movement to said rendering means, automatic means for giving said 50

rendering means the other movement, means for preventing a second operation of said automatic means when a key is retained in depressed position at the end of an operation of the machine, means for disabling said preventing means, and means for preventing the operation of said disabling means during the operation of the machine. 65

23. In a machine of the class described the combination with operating means, of a normally effective locking device therefor, means for rendering said locking device ineffective and having two movements to accomplish this purpose, manipulative means for imparting one movement to said rendering means, automatic means for giving said rendering means the other movement, a pawl carried by said automatic means for preventing a second operation of said automatic means when a key is retained in depressed position at the end of an operation of the machine, and manipulative means for disabling said pawl. 75

24. In a machine of the class described the combination with operating means, of a normally effective locking device therefor, means for rendering said locking device ineffective and having two movements to accomplish this purpose, manipulative means for imparting one movement to said rendering means, automatic means for giving said rendering means the other movement, a pawl carried by said automatic means for preventing a second operation of said automatic means when a key is retained in depressed position at the end of an operation of the machine, manipulative means for disabling said pawl, and means for preventing the operation of said disabling means during the operation of the machine. 90

25. In a machine of the class described the combination with operating means, of a normally effective locking device therefor, depressible keys, means for rendering said locking device ineffective and for locking the depressed keys in depressed position and partially operated by said keys, means for automatically completing the operation of said rendering means, when a key is depressed completely, to render said locking device ineffective, means for retaining said rendering and locking means in partially operated position and for preventing a second operation of said automatic means when a key is held in at the operation of the machine, and means for disabling said retaining means. 105

26. In a machine of the class described the combination with operating means, of a normally effective locking device therefor, depressible keys, means for rendering said locking device ineffective and for locking the depressed keys in depressed position and partially operated by said keys, means 110

- for automatically completing the operation of said rendering means, when a key is depressed completely, to render said locking device ineffective, means for retaining said 5 rendering and locking means in partially operated position and for preventing a second operation of said automatic means when a key is held in at the operation of the machine, means for disabling said retaining 10 means, and means for preventing operation of said disabling means during the operation of the machine.
27. In a machine of the class described the combination with a plurality of de- 15 pressible keys, of locking means therefor prepared for effective operation by operation of said keys, and automatically operated cam means effective upon the preparation of said locking means for actuating the 20 latter to lock the keys in operated position.
28. In a machine of the class described the combination with a plurality of manipulative means, of locking means therefor prepared for effective operation by operation 25 of said manipulative means, and automatically operated cam means effective upon the preparation of said locking means for actuating the latter to lock the manipulative means in operated position.
30. 29. In a machine of the class described the combination with a plurality of depressible keys, of locking means therefor prepared for effective operation by operation of said keys, and automatically operated cam means 35 effective upon the preparation of said locking means for actuating the latter to lock the keys depressed in operated position, and the undepressed keys in normal position.
30. In a machine of the class described the 40 combination with depressible keys, of a detent therefor, having hook projections for locking the keys in depressed position and prepared for effective operation by depression of said keys, and an automatically op- 45 erated member having a cam edge for en- gaging said detent and rendered effective to actuate the detent thereby upon preparation of the latter.
31. In a machine of the class described the 50 combination with depressible keys, of a detent therefor, having hook projections for locking the depressed keys in depressed position and the undepressed keys in normal position and prepared for effective operation 55 by depression of said keys, and an automatically operated member having a cam edge for engaging said detent and rendered effective to actuate the detent thereby upon preparation of the latter.
60. 32. In a machine of the class described the combination with a bank of keys, of a detent having hooked projections for locking the keys in depressed position and inclined edges with which the keys coöperate 65 to operate partially said detent, and a spring operated member having a camming surface for engaging said detent to complete the operation of the latter after it has been operated partially by said keys whereby the latter are locked in depressed position. 70
33. In a machine of the class described the combination with an operating mechanism, of a plurality of depressible keys, locking means for the keys prepared for effective operation by the operation of said keys, automatically operated cam means effective upon the preparation of said locking means for actuating the latter to lock the keys in operated position, and means for preventing a second operation of said cam 75 means when a key is retained in depressed position at the end of an operation of the machine. 80
34. In a machine of the class described the combination with an operating mechanism, of a plurality of depressible keys, locking means for the keys prepared for effective operation by the operation of said keys, automatically operated cam means effective upon the preparation of said locking means for actuating the latter to lock the keys in operated position, means for preventing a second operation of said cam 85 means when a key is retained in depressed position at the end of an operation of the machine, and means for disabling said preventing means. 90
35. In a machine of the class described the combination with an operating mechanism, of a plurality of depressible keys, locking means for the keys prepared for effective operation by the operation of said keys, automatically operated cam means effective upon the preparation of said locking means for actuating the latter to lock the keys in operated position, means for preventing a second operation of said cam 95 means when a key is retained in depressed position at the end of an operation of the machine, and means for disabling said preventing means. 100
36. In a machine of the class described the combination with operating mechanism, of a plurality of keys, a detent therefor partially operated by said keys, automatic means for completing the operation of said detent, means for disabling said automatic means during the operation of the machine, and means for preventing a second operation of said automatic means if a key 105 is retained in depressed position at the end of an operation of the machine. 110
37. In a machine of the class described the combination with an operating mecha- 115

nism, of a plurality of keys, a detent for said keys partially operated by the latter, automatic means for completing the operation of said detent, means for disabling said automatic means during the operation of the machine to permit the release of the depressed keys, and means for retaining said detent in the position to which it is moved by said keys to lock a depressed key in de-

pressed position after the operation of the ¹⁰ machine if the key has been held in until after the proper time for its release.

In testimony whereof I affix my signature in the presence of two witnesses.

HAAKON A. MARTIN.
